UNITED STATES PATENT OFFICE.

WILLIAM P. DUNHAM, OF LOS ANGELES, CALIFORNIA.

VACUUM-CUP-RELEASING DEVICE FOR LAMPS.

1,104,252.

Specification of Letters Patent. Patented July 21, 1914.

Application filed March 25, 1914. Serial No. 827,024.

To all whom it may concern:

Be it known that I, WILLIAM P. DUNHAM, a citizen of the United States, residing at the city of Los Angeles, State of California, 5 have invented certain new and useful Improvements in Vacuum-Cup-Releasing Devices for Lamps, of which the following is a clear, full, and exact description.

This invention relates to portable hand 10 lamps or the like, which are held in place by a vacuum cup.

The object of the invention is to provide a means to readily dislodge the vacuum cup from its holding position without exerting 15 any effort or material pull on the part of the user.

In carrying out this invention, I provide the usual base and column for a stand device, which is generally for the purpose of 20 carrying an electric lamp, and I mount the reciprocating vacuum cup with its stem and spring, and its protruding hand piece for causing the cup to attach itself to a smooth surface within a hollow column supported 25 by the base. In addition to the reciprocating stem for the vacuum cup, I provide a preferably flexible connection such as a wire, cord or chain, which is secured at one end to a lug on the rubber periphery of the vacuum 30 cup, and at its other end is attached to a hand piece preferably slidable on the shank of the attaching hand piece. A spring holds both hand pieces apart, and permits the connection from the second hand piece to the 35 cup to lie idle and slack so that the device may be attached to a smooth surface in the manner hereinafter referred to. Upon the user desiring to release the vacuum cup he grasps the two hand pieces, pinches them 40 together, thereby lifting one edge of the vacuum cup and admitting air thereunder. The device will then readily lend itself to being detached without any effort on the part of the user.

45 The scope of my invention will be pointed out in the claims.

In the accompanying drawings: Figure 1 is a side elevation of my improved lamp. Fig. 2 is a central vertical section of the 50 stand and column. Fig. 3 is an enlarged detail section of the suction cup, the relief position being shown in dotted lines.

As shown in the drawings, my invention 55 consists of the hollow base 1, preferably provided with a reel 2 for the flexible cord which is attached to the connecting plug 3.

A hollow column 4 extends from the base 1, and a tubular post 5 secured to the reel is adapted to rotate within the column 4; an attaching suction cup of rubber 6 carried on the end of a stem 7 and provided with a protruding finger piece 8 is carried within the reel and tubular post for the purpose of permitting a depression of the stem 7 and a flattening of the suction cup 6 against 60 a plain surface, such as glass, so that the device may be supported in the position of Fig. 1. In lamps of this description a very decided effort is necessary in dislodging a lamp from its suction position. According 65 to this invention, I provide a lug 9 at or near the periphery of the suction disk, and I connect a substantially flexible wire 10 to the cup terminating in a finger piece 12 sliding in a guide 13 on the stem of the 70 hand piece 8. A spring 14 normally tends to hold the cup in the position shown in Fig. 2.

When it is desired to detach the vacuum held lamp according to the device of my 75 invention, the finger piece 12 and the finger piece 8 are pinched together with a thumb and forefinger of the hand, the flexible wire 10 caused to lift the lug 9, and admit air under one edge of the suction cup 85 6, so that the spring 14 will immediately retract the cup into the base and detach the lamp without effort that is otherwise necessary.

If desired, a spring 15 may be provided 90 between the two finger pieces to normally hold them in the position of Fig. 2.

I claim as my invention:

1. The herein described portable stand comprising a base, a column, a suction valve 95 mounted so as to be reciprocated in the column, and a controlling device adapted to lift an edge of the suction valve to admit air thereunder.

2. The herein described portable stand 100 comprising a base, a hollow column, a stem passing through the column, and having a projecting hand piece, a vacuum cup mounted at the end of the stem, the column and base supported by the stem, in combination 105 with a second hand piece movable with relation to the first and connected to a portion of the vacuum cup, whereby the vacuum cup may be lifted at one point to admit air thereunder.

3. The herein described portable stand 110 comprising a base, a hollow column, a stem,

- passing through the column, and having a projecting hand piece, a vacuum cup mounted at the end of the stem, the column and base supported by the stem, in combination with a second hand piece movable with relation to the first and connected to a portion of the vacuum cup, whereby the vacuum cup may be lifted at one point to admit air thereunder, said second hand piece reciprocable with the first hand piece.
4. The herein described portable stand comprising a base, a hollow column, a stem passing through the column, and having a projecting hand piece, a vacuum cup mounted at the end of the stem, the column and base supported by the stem, in combination with a second hand piece movable with relation to the first and connected to a portion of the vacuum cup, whereby the vacuum cup may be lifted at one point to admit air thereunder, said second hand piece reciprocable with the first hand piece, a spring normally holding the two hand pieces together.
5. The herein described portable stand comprising a base, a hollow column, a stem

passing through the column, and having a projecting hand piece, a vacuum cup mounted at the end of the stem, the column and base supported by the stem, in combination with a second hand piece movable with relation to the first and connected to a portion of the vacuum cup, whereby the vacuum cup may be lifted at one point to admit air thereunder, said second hand piece reciprocable with the first hand piece, a spring normally holding the two hand pieces together, a flexible connection between the second hand piece and the vacuum cup.

6. The herein described stand having a vacuum cup, a lug integral with the vacuum cup near its perimeter and means for lifting the lug to uncover a portion of the perimeter in advance of the entire edge of the cup.

Signed at New York city, New York, this 23rd day of March 1914.

WILLIAM P. DUNHAM.
